AIR CONDITIONING APPARATUS

Texas A. Milholland, Little Rock, Ark.

Application March 25, 1938, Serial No. 198,128

2 Claims. (Cl. 261—9)

My invention relates to improvements in air-conditioning apparatus for use more especially in stores and small dwellings.

The principal object of the invention is to provide a simplified form of air-conditioning apparatus whereby air can be cooled in hot weather and heated in cold weather.

Another object of the invention is to provide an apparatus of the character indicated where-
10 in air can be treated so as to raise or lower the temperature and can concurrently be conditioned for distribution.

During the course of the following specification, other important objects and advantages of
15 the invention will become apparent to the reader.

In the drawings accompanying and forming part of this specification:—

Figure 1 is a view in front elevation of my im-
proved apparatus,

20 Figure 2 is a view in side elevation looking at the right-hand side of the apparatus,

Figure 3 is a bottom plan view,

Figure 4 is a view in rear elevation,

25 Figure 5 is a fragmentary perspective view of the air-conditioning unit detached from the cabinet and looking at the right-hand side of said unit,

Figure 6 is a view of said air-conditioning unit
30 detached and shown partly in front elevation and partly in longitudinal section,

Figure 7 is a view in transverse section of the air-conditioning unit taken on the line 7—7 of Figure 6 and drawn to an enlarged scale.

Referring to the drawings by numerals, the
35 apparatus of my invention comprises a substan-
tially rectangular cabinet A opened at its back and at the bottom thereof and in which is suit-
ably mounted the base structure, or bottom, 6. Suitably secured in the upper part of the cabi-
net A and spaced above the structure 6 is an

40 air-conditioning unit designated, as a whole, by the numeral 7 and shown detached in Figures 5,
6 and 7. The air-conditioning unit 7 comprises an outer shell having a dome-shaped top 9 and
45 the bottom wall 10. On the inside of the air-
conditioning unit 7 is the secondary wall 11 which
rises from the bottom wall 10 and curves in-
wardly as at 12 to terminate in the backwardly
disposed baffle plates 13 spaced apart upon op-
50 posite sides of the longitudinal center of a cham-
ber formed by said wall 11 and the ends and
bottom 10 of the shell 8. As will hereinafter
more clearly appear, the chamber 26 thus formed
55 constitutes a coil chamber and said baffle plates
13 define an air outlet therebetween at the top

of said chamber. Extending from a point in closely spaced relation to the bottom 10 and between one side wall of the shell 8 and its op-
posed wall 11 is the partition 14 which extends
vertically on one side of the shell across under
the top 9 and down between the outer side wall
of shell 8 and the secondary wall 11 to terminate
in closely spaced relation to the bottom 10. This
continuous partition 14, for a purpose presently
explained, is provided with small openings 15 in 10
the uppermost portion thereof and underlying
vents 16 in the top 9. The vents 16 terminate
within the expansion tubes 17, which expansion
tubes extend upwardly from the top 9 through a
box structure 18 mounted on the top 9 and into 15
which fresh air ducts 19 open. The expansion
tubes 17 are provided with openings 20 com-
municating the vents 16 with the box 18.

As will presently more clearly appear, the par-
tition 14 forms together with the said wall 11, a 20
pair of inner passageways 21 in the shell 8 ex-
tending from opposite sides of the opening de-
fined by the baffle plates 13 upon opposite sides
of the coil chamber 26 to the bottom wall 10, and
further forms, together with the side walls of 25
shell 8 and top 9 thereof, a pair of outer passage-
ways 22 in said shell leading upwardly from the
bottom 10 of the shell upon opposite sides of said
chamber 26 and to the vents 16 and communi-
cating at the lower ends thereof with the pas-
sageways 21. As will also presently appear, the 30
secondary wall 11 functions as a baffle for con-
densation which drains down the inner face
thereof to the bottom of the chamber 26 and out
of the latter by way of openings 11' provided in 35
the lower end of said wall 11 and leading into
troughs 8' formed in the bottom 10 between the
side walls of the shell 8 and said secondary
wall 11.

40 Mounted upon the base 6 is the electric motor 23 which drives a suction fan in the housing 24
for drawing air into the ducts 25 and forcing the
same upwardly into the chamber 26 where the
two coil units 27, 28 are located. Outlet and in-
let pipes 29, 30 are connected with these coils 45
for the purpose of supplying hot water or cold
water thereto and also for the purpose of supply-
ing water to the perforated pipes 31, 31, which
are located immediately adjacent the baffle plates
13. The housing 24 is designed to contain a 50
filter, not shown.

55 It is desired that the humidity and tempera-
ture control unit referred to by numeral 32 on
one side of the machine (see Fig. 1) be employed
for controlling the water supply to the perfo- 55

rated pipes 31, 31, for humidifying the air. For this purpose a magnetic valve 38 is interposed in the line of connection between the perforated pipes 31, 31 and the outlet pipe 29 which is operated in any suitable manner under control of the unit 32 to vary the supply to said pipes 31, 31. Any condensation accumulating in the troughs 8' is collected by the drain pipes 33, 34 and discharged into the container 35 which is located below said pipes on a spring-supported plate 36 on one side of the machine urged upwardly to position the mouth of the container 35 against a cock 35' on the pipe 34.

The bottom of the apparatus is provided with 15 a mesh air inlet 37 as shown in Figure 3. The numeral 39 designates a motor-controlling switch.

Referring to the operation of the described apparatus, when used as a cooling apparatus, the outside air is drawn into the housing 24 by 20 the fan therein, not shown, and forced upwardly through the ducts 25 into the coil chamber 26, such air being cleaned by the filter, not shown, in said housing 24. The temperature in the coil chamber 26 is lowered by means 25 of cold water circulated through the coils 27, 28 by way of the inlet and outlet pipes 30 and 29, below the dew point and blown against the secondary wall 11 and out of the chamber between the baffle plates 13 against the partition 30 14. Because of the fact that the temperature of the air is lowered to the point indicated, moisture therein condenses both on the secondary wall 11 and partition 14 so that these elements function as de-humidifying baffles by removing the 35 moisture from the air. The condensation on the inner face of the wall 11, that is to say, in the chamber 26, drains out by way of the apertures 11' into the troughs 8' and that on the partition 14 drains down the same into said troughs, the 40 accumulation in said troughs being carried off by the pipes 33 and 34. In this described de-humidifying process, the heat abstracted from the air is carried off with the condensation, the air further cleaned, and harmful vapors carried away. By 45 enclosing the coil chamber 26, substantially, by the partition 14, the air is pocketed around said chamber 26 whereby, and due to its low temperature, such air is further cooled quickly by the coils 27 and 28. The thus cooled and cleaned 50 air is now blown downwardly out of the passageways 21 and upwardly by way of the passageways 22 into the expansion tubes 17 by way of vents 16. In this connection, the openings 15 in the 55 partition 14 are vertically aligned with the axes of the tubes 17, and the air issuing therefrom, under pressure, enters said tubes and increases the velocity of the aggregate air passing through said tubes. Due to expansion of the air in said tubes 17, and such increased velocity thereof, a 60 partial vacuum is created in said tubes 17 thereby drawing into the tubes outside air from the box structure 18 and by way of the openings 20, such outside air being mixed with the air in said tubes 17 and blown therewith out of said tubes 65 into the atmosphere. In this mixing process said outside air is cooled by the processed air entering said tubes 17 from the passageways 22. The quantity of outside air admitted to said tubes 17 is controlled primarily by the size of the openings 20.

By the above described process, a room may be cooled to the desired temperature without cooling all the air in the room in the apparatus. The air pressure in the apparatus may be controlled by the speed of the fan.

When using as a heating apparatus, hot water, or steam, under pressure, is circulated through the coils 27 and 28 by way of the inlet pipe 30 and outlet pipe 29. Otherwise the operations are as above explained for cleaning and purifying the air blown through the apparatus.

The perforated pipes 31, 31 function as humidifiers or de-humidifiers, as the case may require. When cooling, cold water is introduced into said pipes 31, 31 from the outlet pipe 29 to be sprayed therefrom as desired. When heating, hot water, or steam, is similarly introduced into said pipes 31, 31 and sprayed therefrom. The density of the spray is controlled by operation of the before-mentioned magnetic valve 38 under control of the unit 32.

While the foregoing sets forth the invention in specific terms, it is to be understood that numerous changes in the shape, size and materials, may be resorted to without departing from the spirit and scope of the invention as claimed herein-after.

Having described the invention, what is claimed as new is:

1. Air conditioning apparatus including a substantially rectangular shell comprising a bottom, outer and inner side walls arising from said bottom in spaced apart parallel relation, and outer and inner top walls spaced similarly to the side walls, the inner top wall having a longitudinally extending central outlet therein and forming together with the inner side walls and said bottom an air cleaning chamber, an air inlet duct secured to said bottom and opening into said chamber, a blower fan in the line of said duct for introducing outside air under pressure into said chamber to discharge out of said outlet, coils in said chamber for treating the air in the latter, a baffle in said shell intermediate said outer and inner walls and dividing the space between said walls into inner and outer passageways communicating at the bottom of said shell on opposite sides thereof and whereby the treated air discharged from said outlet is forced downwardly from opposite sides of said outlet along opposite sides of the chamber and then upwardly to the top of said shell, discharge nozzles in the outer top wall spaced along the longitudinal center thereof for the escape of treated air from the outer passageway, expansion tubes arising from said nozzles to discharge the air issuing from the latter into the outside atmosphere and having inlet ports in the lower ends thereof, a box-like manifold extending along said top wall and through which said expansion tubes extend, and a duct leading into said manifold for introducing outside air into the latter to be drawn through said port into the expansion tubes for mixing with the treated air therein and discharge therewith.

2. Air conditioning apparatus including a substantially rectangular shell comprising a bottom, outer and inner side walls arising from said bottom in spaced apart parallel relation, and outer and inner top walls spaced similarly to the side walls, the inner top wall having a longitudinally extending central outlet therein and forming together with the inner side walls and said bottom an air cleaning chamber, an air inlet duct secured to said bottom and opening into said chamber, a blower fan in the line of said duct for introducing outside air under pressure into said chamber to discharge out of said outlet, coils in said chamber for treating the air in the latter, a baffle in said shell intermediate said outer and inner walls and dividing the space between

said walls into inner and outer passageways communicating at the bottom of said shell on opposite sides thereof and whereby the treated air discharged from said outlet is forced downwardly 5 from opposite sides of said outlet along opposite sides of the chamber and then upwardly to the top of said shell, discharge nozzles in the outer top wall spaced along the longitudinal center thereof for the escape of treated air from the outer passageway, expansion tubes arising from said nozzles to discharge the air issuing from the latter into the outside atmosphere and having in-

let ports in the lower ends thereof, a box-like manifold extending along said top wall and through which said expansion tubes extend, and a duct leading into said manifold for introducing outside air into the latter to be drawn 5 through said port into the expansion tubes for mixing with the treated air therein and discharge therewith, and spray pipes extending along each side of the outlet of said treating chamber for humidifying the air issuing from the latter. 10
